CONNECTOR PLUG

Arthur Brownstein, Bridgeport, Conn.

Application January 5, 1940, Serial No. 312,448

3 Claims. (CL 173—361)

This invention relates to electrical connector plugs, and more particularly, to connector plugs used with extension cords or conductors for making separable electrical connection to an electrical appliance with a socket in an electrical circuit.

The connector plug of the present invention is preferably formed of some rigid plastic material which can be easily molded, and yet sturdy enough to withstand the usage to which such plugs are put.

The plug body is formed with a pair of spaced blade-receiving slots which extend into the plug from one face thereof and a single cavity opening into the other face of the plug for receiving the end of a conductor, the cavity communicating with the inner ends of the spaced blade-receiving slots so that the bared end of the conductors may be brought into engagement with the metallic contact blades. The blade-receiving slots of the body are so formed that the blades, when inserted into the same to their proper assembled position, cannot be moved farther into the plug as when the blades are pushed into the receptacle, and, to prevent the blades from being pulled out of the plug body, means are formed on each blade for anchoring the same in the slots against removal.

The blades which are firmly locked in position after they have been properly assembled can be quickly and easily secured in place without the use of complicated tools, and in such a manner that they firmly secure the ends of an extension cord or conductor to the plug and at the same time make electrical contact with the bared wires of the cord.

In prior contact plugs, tangs have been utilized to anchor blades in slots in the plug body. However, in these constructions, the tang, which is of resilient material, is forced from its normal position as it passes through the slot and then relies solely upon the resiliency of the tang to snap it into engagement with an abutment.

It is preferred, according to the present invention, however, to provide a tang which does not rely solely upon the resiliency of the prong for moving it into locking engagement with the abutment, but which is positively forced into engagement with the abutment to firmly lock the blade in the slot. While the tang may be resilient and move into cooperative relation with the abutment when the blade is in place, it is contemplated positively moving it farther into locking relation.

A further feature of the present invention,

therefore, is to provide a rugged and efficient electrical connector plug easily molded in one piece, which can be easily assembled without the use of complicated tools.

5 Other features and advantages will hereinafter appear.

In the accompanying drawing:

Figure 1 is a perspective view of the connector plug of the present invention showing the contact blades in assembled position.

10 Fig. 2 is a sectional view of the plug shown in Fig. 1, with the contact prongs removed.

Fig. 3 is a view taken along line 3—3 of Fig. 2.

15 Fig. 4 is a sectional view taken along line 4—4 of Fig. 2.

Fig. 5 is a view similar to Fig. 2, but showing the contact blades in assembled position and in contact with the bared ends of the wire of the extension cord.

20 Fig. 6 is a view taken along line 6—6 of Fig. 5.

Fig. 7 is a perspective view of a contact blade which may be used with the plug shown in the figures just referred to.

25 Fig. 8 is a view similar to Fig. 7, but showing a different contact blade.

The connector plug of the present invention includes a body 10 made of rigid plastic material, or any other suitable insulating material, and preferably is made, as shown, in one piece.

30 It is provided with a pair of blade slots 11 for receiving and supporting a pair of contact blades 12. When the blades 12 are properly assembled in the body, operative portions thereof project from a face 13 of the body while a cable 14, the wires 15 of which are to be electrically connected to the blades, projects from the other end of the plug body through a cavity 16.

The cavity 16 merges with the blade slots 11 so that the individual conductors of the cable 14 can be led up into the blade slots. A suitable shaped lug 17 projects into the cavity 16 and serves to space the wires in the cavity.

40 It will be seen, referring to Fig. 2, that the single cavity 16 communicates with the blade slots 11 intermediate their ends so that there is formed a pair of pockets 18 in which rests the inner ends of the contact blades 12 when the same are properly assembled within the plug body.

45 In assembling the cable and plug, the end of the cable 14, with the end of the wires 15 thereof bared, is inserted into the cavity 16. The bared ends of the wires are placed in the blade slots 11 so as to extend thereacross. The blades are then inserted into their respective slots until

the bared end of the wires are tightly clamped against the end wall of each blade slot.

As will be seen from the drawing, the slots 11 are of a width to receive and hold the blades in position against lateral movement. Each of these slots is provided with a bowed portion 11a communicating with the slot and into which the end of the wire is positioned when the blades are in place, as will be shown in Fig. 5.

The slots are also provided with a second 10 communicating opening 11b, which opens to the inner side of the slot and extends therewith so as to be adjacent the abutment, as shown in Figs. 2 and 5.

With the opening 11b so arranged in each 15 slot, the blade having a tang projecting therefrom can be inserted. After the blade is in position in the slot, a bending tool can also be inserted in the opening and along the blade into engagement with the tang, as will be explained.

To anchor the blades in the blade slots of the plug of the present invention, each blade is provided with a projecting tang 19 which is formed by lancing a portion from the blade and then striking down the same so that the tang 20 projects, with slight angularity, from the one face of the blade. The blades are inserted into the blade slot so that the tangs 19 project toward each other and pass along the opening 11b. The lug 17 is formed at the upper end with a pair 25 of diverging shoulders 20 which provide surfaces against which the outer end of the tangs may engage to prevent the blades from being pulled outwardly of the plug body.

The angle on the divergent inserts is such that the radius of a circle passing from the bending point of the tang will intersect the face thereof. This, as will be more fully explained, will cause the tang, when moved into engagement therewith, to be rigidly locked in the slot.

In the now preferred manner of assembling the contact blades, the blades are inserted into the blade slots and the bared ends of the conductors are tightly clamped against the end wall of the blade slots, and then a suitable tool (not shown) is inserted into the openings 11b and force is applied to strike down the tangs 19 until the same pass the shoulders 22 and engage the diverging surfaces of the lug 17.

As was explained above, the angle of the diverging shoulders is such that the tang, when being bent about its base, will be forced into engagement with the surface thereof so as to react thereagainst to press the end of the blade engaging the wire in the slot into better electrical engagement therewith. The tang, in so moving into engagement with the diverging surfaces of the lug 17, will bite into the material of said surfaces which will prevent the tang from being bent around and into the passage between the slot 11 and cavity 16 where it might not firmly anchor the blade.

It will be seen that the contact blades will thus be effectively locked in position against longitudinal movement of the blades with respect to the plug. It will, of course, be impossible to move the blades to the rear of the plug as the inner ends of the blades engage the end walls of the blade slots. It will also be impossible to move the contact blades outwardly of the plug body because of the interlocking engagement between the tangs and the diverging surfaces of the lug 17.

When the blades are locked in the slots, good electrical engagement is insured between wires

13 of the cable 14 and the contact blades, for, as will be seen, the bared ends of the wires are tightly clamped between the end walls of the blade slots and the inner ends of the blades.

The contact blade, shown in Fig. 7, may be used with the connector plug previously described, which, as will be seen, consists of a solid piece of conducting material from which the tangs 19 have been lanced.

A modified form of the blade is shown in Fig. 8, and this blade consists of a single strip of suitable conducting metal bent upon itself as at 23 to form a contact blade having two legs of equal length. The tang 19 is formed on this blade, as in the just described blade, by stamping and bending so that it projects outwardly as shown. Either form of the contact blade may be made from a piece of suitable conducting material, such as brass, or may be made from a body of aluminum and then suitably coated as described in my copending application Serial No. 312,447 filed concurrently herewith.

It will be seen that the connector plug of the present invention may be easily molded from some cheap plastic material and the contact blades may be quickly and easily assembled therewith without the use of complicated tools. Further, the blades, once assembled, are securely locked in their proper position against removal.

Variations and modifications may be made within the scope of this invention and portions of the improvements may be used without others.

I claim:

1. An electrical connector plug including a single piece body of insulating material, said body comprising a pair of parallel slots extending into the same in one direction, a single cavity extending into the body in opposition to said first direction and a pair of passageways diverging from said cavity, each passageway communicating with a slot intermediate the ends thereof, the one wall of each passageway at the entrance thereof into the slot forming an angularly extending shoulder having a flat surface facing the inner end of the slot; a contact blade disposed in each slot; a cord comprising a pair of conductors received within said cavity, the bared end of each conductor extending through a passageway and reversely bent to lie within the inner end of a slot; and rigid tangs lanced from said blades and disposed adjacent the entrance of said passageways into said slots when the blades are positioned in the latter, each tang being adapted to be forcibly bent over about one end into engagement with its adjacent shoulder, the angularly disposed flat surface intersects the arc through which the end of the tang moves when forcibly bent whereby the end bites therein and locks the blade in the slot and forces the blade inwardly so that the bared end of the conductor is clamped between the end thereof and the inner wall of the slot.

2. An electrical connector plug including a single piece body of insulating material, said body comprising a pair of parallel slots extending into the same in one direction and adapted to receive contact blades; a single cavity extending into the body in opposition to said first direction and a pair of passageways diverging from said single passageway, each passageway communicating with a blade slot intermediate the ends thereof, the one wall of each passageway at the entrance thereof into the slot forming a shoulder angularly extending relative to said slot and facing the inner end thereof; a contact blade disposed

in each slot, each contact blade being formed of flat conducting material bent upon itself to form two blades of equal length having the outer ends thereof integrally joined together; a cord comprising a pair of conductors received within said cavity, each conductor of said cord having a bared end thereof extending through a passageway and reversely bend to lie within the inner end of said slot; and means for camming the ends of said blades against the inner walls of said slots, said means comprising portions partially lanced from both legs of each contact blade and forming a tang angularly projecting from one face of the blade to a point adjacent a shoulder, each tang being adapted to be forcibly bent over into engagement with its adjacent shoulder, the angularly disposed surface intersecting the arc through which the end of the tang moves and camming the blades against the inner walls of the slots with the bared end of each conductor tightly clamped between the end of each blade and the inner wall of the slot, the ends of the tangs biting into said shoulder and holding the blade in said position.

3. In an electrical connector plug including a single piece body of insulating material, said body being formed with a pair of parallel slots extending into the slots in one direction, a single cavity extending into the body in opposition to said first direction and a pair of passageways di-

verging from said single cavity, each passageway communicating with a slot intermediate the ends thereof, the one wall of each passageway at its entrance into the slot forming a flat angularly extending shoulder facing the inner end of the slot; a twin conductor cord received within said cavity, the bared ends of each conductor thereof extending through a passageway and reversely bent to lie within the inner end of a slot; a contact blade disposed within each slot; and a rigid tang having a flat end face angularly projecting from one face of each blade in the direction of the shoulder, said slots having a communicating opening of less width than the blade and extending therealong to a point adjacent the shoulder and permitting the tang on the blade to pass therealong and a tool to be inserted into said body for forcibly bending each tang into engagement with a shoulder, the shoulder being so angularly disposed with relation to the slot that the flat end face of the tang, when the latter is bent about its base, engages the flat surface thereof whereby the blade is cammed inwardly and forced into engagement with the bottom of the slot with the bared end of the conductor therebetween, the flat end face of the tang biting into the flat surface of the shoulder and rigidly holding the blade against movement relative to the slot.

ARTHUR BROWNSTEIN.
